(57) CLAIM

The ornamental design for a cosmetic pencil, as shown and described.

DESCRIPTION

FIG. 1 is a front view of a cosmetic pencil showing my new design, shown with the cap off to show aspects of the design that are not visible when combined;

FIG. 2 is a rear view thereof;

FIG. 3 is a left side view thereof;

FIG. 4 is a right side view thereof;

FIG. 5 is a bottom view thereof;

FIG. 6 is a top view thereof;

FIG. 7 is a perspective thereof;

FIG. 8 is another perspective of the cosmetic pencil with the cap on; and,

FIG. 9 is an enlarged view of the right side view in FIG. 4. In the drawings the broken lines represent portions of the cosmetic pencil which form no part of the claimed design.

1 Claim, 8 Drawing Sheets
